UNITED STATES PATENT OFFICE.

GIANNI BETTINI, OF PARIS, FRANCE.

PLATE AND PLATE-HOLDER FOR MOVING-PICTURE APPARATUS.

1,242,416.

Specification of Letters Patent.

Patented Oct. 9, 1917.

Continuation in part of application Serial No. 642,250, filed August 4, 1911. This application filed October 5, 1916. Serial No. 123,825.

To all whom it may concern:

Be it known that I, GIANNI BETTINI, a subject of the King of Italy, and a resident of Paris, France, have invented a new and 5 useful Improvement in Plates and Plate-Holders for Moving-Picture Apparatus, of which the following is a specification.

This application is, in part, a division of my application Serial No. 642,250 filed August 4, 1911, entitled Moving picture apparatus and, in part, a continuation of said application.

My invention relates to moving picture apparatus and particularly to a form of such apparatus in which the optical system used for projection or for picture taking is displaced with relation to a plate upon which are the images to be projected, or upon which the pictures are to be taken, said plate 20 having a fixed position relative to the picture being taken or the screen upon which they are projected instead of, as in the usual apparatus, displacing the plate with relation to a fixed optical system. More particularly 25 my invention relates to apparatus of the above mentioned type, in which the pictures are projected upon or taken from a plane at right angles to the plane of the relatively fixed plate.

It is the object of the present invention to provide a form of plate and plate holder to be used with my apparatus of the above described type as claimed in my earlier application above referred to and as described 35 therein and also below in the present application. The invention can be applied to ordinary photographic plates of small size easily obtained at relatively small cost.

In order that the invention may be readily understood I have shown in the accompanying drawings an embodiment of the preferred form of machine for utilizing the plate holder of said present invention and in the text which follows I have described 45 said machine.

In the drawings, Figure 1 is a diagram showing the principle upon which the invention is based; Fig. 2 is a general view of the box containing the mechanism, the 50 cover being omitted; Fig. 3 is a section on the line 3—3 of Fig. 2; Figs. 4 and 5 are end views of the box represented in Figs. 2 and 3 from the right and left hand sides respectively; Fig. 6 shows a plate magazine intended to be fitted to the projection

apparatus; Fig. 7 is a section of the plate magazine on the line 7—7 in Fig. 6; Fig. 8 is a detail view of a plate with its plate holder frame; Figs. 9 and 10 are detail views of the plate and plate frame; and Figs. 11 to 14 are detail views showing a modified form of plate frame.

The principle upon which the apparatus is constructed is represented diagrammatically in Fig. 1 and provides for illuminating the photographs from a fixed source of light B including the usual condenser for projecting a pencil of parallel luminous rays, the axis of which would first of all be parallel with the plane of the plate or band A carrying the pictures instead of falling perpendicularly upon it as in all other methods of projection. The axis of the luminous pencil is then directed perpendicularly to the plate or band by means of a prism or other reflecting surface C which would deflect it from the parallel direction.

By means of an objective D combined with another prism or reflecting surface E and arranged on the other side of the plate or band the image is then projected on to a screen F arranged perpendicularly to the plane of the plate or band or in any other plane by employing suitably arranged supplementary reflecting surfaces.

In displacing the objective D and the prism E and the reflecting prism C with an intermittent synchronous reciprocating movement parallel with the plate or band A, the focusing is not altered and the photographs of the same row upon said plate will be successively illuminated and projected upon the screen F. It will thus only be necessary to lower or shift the plate or band A transversely of the path of movement of the objective at the end of each travel of the optical system for obtaining the projection of the next following row of pictures.

During the displacement of the objective D and prisms E and C, the field of exposure or of projection experiences a slight diminution or increase of size which is imperceptible to the eye, which increase or decrease being gradual and exceedingly small, becomes confused with the increase or decrease of size experienced by the objects photographed according as they approach or recede from the apparatus.

In projection this increase takes place in the reverse sense to what occurs when the

5 pictures are taken because the smallest image (that which is most distant from the screen) will be enlarged the most, while the largest image (that which is the closest to the screen) will be less magnified and consequently the increase of size in projection taking place in the opposite sense to what occurs when the pictures are taken the projection will be absolutely fixed even if the difference in size between the images should be very considerable.

10 In cases where bands of films are employed instead of plates, these films (of suitable size) would have the pictures arranged as on the 15 plates, that is to say, in successive rows and these bands would be arranged in the apparatus on rollers behind the objective as in the case in photographic apparatus of the Kodak type.

20 As a modification of the system comprising the fixed source of light B and reflecting prism C described above any convenient source of light of small volume (Nernst lamp of suitable dimensions rendered incandescent, etc.) combined with a small condenser might be employed and without the use of any reflecting prism this arrangement would illuminate the views directly and in succession if displaced synchronously with 25 the objective.

30 One and the same apparatus based upon the principle described is adapted with equal facility for taking animated pictures and for projecting them. For taking the pictures with the apparatus closed and forming a dark chamber it will be sufficient to utilize sensitized plates or films; the source of light B and the reflecting prism C would then not be utilized.

40 Both in taking pictures and in projecting them all the movements of the optical system would be masked by an appropriately arranged shutters.

45 As regards the mechanism proper, the apparatus comprises a metal or other suitable box *a* provided with an intermediate partition or base plate *b* intended to support the mechanism within the box (see Figs. 2-5). Bearings *c*, rigidly connected with this partition, support cam screws *d*, *e* of contrary but equal pitch, carrying respectively at one of their ends pinions *f* and *g* (Fig. 2) in mesh with a toothed wheel *h* common to them, both of which is mounted upon the shaft of a 55 bevel pinion *i* which is in mesh with and controlled by a bevel wheel *j* (Fig. 3) keyed to the shaft *k* of the operating handle *m*.

60 A slideway *n* formed on the base plate *b* serves as a guide for a sliding reciprocating carriage *o* carrying the objective *p* and the prism of reflector *p'* shown graphically as D and E in Fig. 1. This carriage also supports a transversely disposed lug bored out or provided with a slot in which there is 65 mounted a rod *r*, the ends of which are

adapted to engage alternately with the cam grooves of the two cam screws *d*, *e*. The carriage *o* carrying the objective is connected in any suitable manner as by a band *s* with another carriage *t*, slideable longitudinally of rod *t'*, and carrying the second prism *t* arranged in front of the source of light. This band passes over spring boxes *u* and *v*, and over rollers *w*, in order to insure synchronous displacement of the prism *t* and the objective *p*. A circular screen *y* is revolvably mounted upon a laterally extending lug *o'* upon the support *o* of the objective and is provided with external gear teeth whereby its movement is controlled by the longitudinal gear teeth on the cam screw *e*. The bottom of the threads of the cam screws *d*, *e* rise at each end of these screws as at *w* and die away on the outer surface of the respective screws, so that when the rod *r* reaches the end of the cam in one screw, it is forced out of engagement therewith and the opposite end enters the cam of the other cam screw, thereby insuring reciprocating operation of the carriage *o* carrying the objective.

Upon the shaft of the cam screw *e* there is mounted a spiral gear *l* which meshes with another spiral gear *2* upon the shaft of which a cam screw *3* is mounted in such a way as to enable it to mesh with teeth *6* on a plate holder frame *7* (Figs. 3 and 5). The pitch of the cam screw *3* is the same as the distance between the teeth *6* of the frame *7* which is adapted to carry the plate *8* (Fig. 9). For the purpose hereinafter stated, the assemblage is mounted to oscillate around the shaft *19* and is acted upon by the spring *20* which is adapted to move the assemblage in one direction and normally to hold screw *3* out of mesh with teeth *6*. A toothed wheel *21* driven by a toothed pinion *22* rigid with the wheel *h* carries a tappet *23*, which is adapted at each revolution of the wheel to strike the cam-boss *5* located on a yoke *4* connected with the assemblage, which, as previously stated, is pivoted at *19*. The rocking of the assemblage is for the purpose of moving the cam screw *3* into and out of mesh with the teeth *6* at the proper intervals. The relation between the number of teeth on the gear *21*, pinion *22*, gear *h* and pinions *f* and *g* is such that the carriage *o* is driven from one end of its run to the other during the intervals of contact of the tappet *23* with the boss *5*.

When the tappet *23* contacts with boss *5* the assemblage is rocked about *19* against the pull of the spring *20* to throw the cam screw *3* into engagement with the teeth *6*. The continued rotation of the cam screw while in mesh with teeth *6* feeds the plate *8*, and such feeding continues until the tappet *23* passes off boss *5*, thus enabling the spring to retract the assemblage. The tap-

pet and boss are so arranged that the assemblage is retracted after the plate has moved a distance corresponding to that between successive rows of pictures, thus feeding the plate one step, or to the next row of pictures.

Each plate 8 is mounted by one of its edges in a frame 7. Each plate is provided with a notch 24 (Fig. 8) corresponding to a tooth or other suitable stop 25 arranged in the frame so that the plates can always be placed in exactly the same position relatively to the frame and thus each picture be brought into exactly the same position in front of the objective. Each frame 7 is furnished on its ridge or corner edge with rack teeth 6, as previously described, the distance between which corresponds with the height of the pictures on the plate. The plate 8 is adapted to be held in position in the frame by leaf springs 18 (Fig. 10).

The plates and frames are arranged in proper order in a plate magazine, which is represented in Figs. 6 and 7 and comprises a box 9 furnished on its rear face with a door 10 for loading, and provided on one of its faces with a suitable number of springs 11 serving to press the plate frames 7 toward a slot 12 through which the plates and frames may be removed from the magazine. The magazine is placed on the box α in such a way that slot 12 registers with slot 15 in casing α . The front face of box 9 is provided with one or more slots 13 and one or more tappets 14 by means of which the foremost plate may be depressed, at the commencement of the operation of the machine so that its teeth 6 engage with the cam screw 3.

As shown in Figs. 7 and 9 each plate frame 7 is provided with projections 17 and notches 16, the projection of one plate being adapted for engagement with the notch 16 of the succeeding plate, so that as one plate finally leaves the magazine the succeeding plate will be pressed into operative engagement therewith by springs 11 and be pulled downward so that eventually each plate will follow the other without interruption, in such a manner that pictures may be taken or projected during a long period of time.

The operation is as follows:

The plate magazine 9 is arranged in place on the projection casing α , care being had that the slot 12 registers with the slot 15, any convenient device being provided for insuring the correct position of the two casings and keeping them in this position. The tappet 14 is depressed to cause the first plate to descend with its frame so that they occupy the position represented in Fig. 3. The prism t is then in front of the first picture of the lower row of this plate.

If the mechanism be operated by means of the handle m the parts occupying the position represented in the drawing and the

rod r in mesh with the thread of the screw d ; the objective and the two prisms p and t as a whole are displaced toward the right hand with an intermittent movement advancing when the rod r is in the inclined part of the cams which then correspond to a change of picture, while the whole remains stationary during the time that this rod traverses the straight part of the cams. During the displacement of the carriages o and t' the screen y is interposed in front of the objective p during the entire time that the rod r is traversing the inclined part of the cam grooves.

When the objective carrier (carriage o) has reached its extreme right hand position the rod r is pressed back by the part w of decreasing depth of the thread of the screw d and meshes with the corresponding part of the thread of the screw e . At the same time the rotation of the wheel 21 carrying the tappet 23 has brought the latter into contact with the boss 5 on the yoke 4 and produces an oscillation around the shaft 19 of the assemblage comprising the yoke and the cam screw 3 which, as pointed out is adapted to mesh with the teeth 6 on the plate frame 7 and causes the latter to descend to the extent of the height of a picture in such a manner that the objective is situated in front of the second row of pictures on the plate. If the handle m is further rotated in the same direction, the rod r being in mesh with the thread of the screw e which are on the same pitch as those of the screw d , but opposite in direction, the same intermittent displacement of the objective carrier o and of the prism t is obtained, but in the reverse direction.

This operation continues until each of the second row of pictures comes in front of the objective when the operation of shifting the plate is repeated. During the descent of the plate, the projection 17 of its frame coming opposite the recess 16 in the following frame engagement takes place (Fig. 9) being produced by the thrust of the springs 11 in such a manner that the plate which is being projected carries with it the following plate which becomes arranged in the manner already stated and the projection continues until the plates contained in the magazine 9 are exhausted.

In the arrangement of plate and plate frame shown in Figs. 11 to 14 the frame 120 comprises a rack member 26 made from flat metal strip slightly thicker than the plate itself. One edge of this rack member is provided with teeth 27 for engagement with the cam screw 3 while its opposite edge has a deep groove 28 to receive the edge of the plate. One side wall of this groove at one end of member 26 is cut away in such fashion as to, preferably, leave a portion attached to the extreme end tooth as at 28. 130

The material between the last two teeth, 29 and 30, and between tooth 30 and the next adjacent tooth 31 is also cut away completely on that side of the rack member from 5 which the groove wall has been removed.

The other end of the same side wall of rack member 26 is extended beyond the end of the rack teeth sufficiently to enable a hook member 32 to be formed at the extreme 10 end thereof said hook member lying next an adjacent space having the width of a rack tooth and this space being separated from the next inner rack tooth by a space equal to the space between the rack teeth.

15 Immediately adjacent to an appropriate edge of each plate there is cemented, or otherwise suitably attached, a plate positioning member 33 of thin metal strip provided with a projecting locking piece 34.

20 This edge of the plate is inserted into the groove 28 of the rack member so that the locking piece 34 fits between rack teeth 30 and 31, thus preventing any linear shifting of the plate in the groove. To prevent the 25 plate from slipping out of the groove 28, the inner wall of said groove on the side opposite strip 33, is provided with a leaf spring pressure member 34' preferably attached to said wall at its central point. This 30 pressure member should be of spring metal and be given a preliminary set so that its end portions press against the sides of the plate and hold it firmly against the opposite wall of the groove 28.

35 The space between teeth 30 and 31 and the locking piece 34 correspond respectively with the notch 16 and projection 17 of the plate and plate frame shown in Figs. 6 to 10.

The modified form of plate and plate 40 frame shown in Figs. 11 to 14 may be used with a plate magazine as in the form first shown or without a magazine the successive plates being fed into the slot at suitable times by engaging the locking piece 34 with 45 the space between teeth 30 and 31 of the preceding plate.

It will be understood that various other modifications in the mechanical details of construction may be made without depart-

ing from the spirit and scope of my invention as claimed. 50

Having described my invention, I claim:

1. In a plate cinematograph, a plurality of frames or slides for receiving the plates, each provided at one end with a notch and 55 at the other end with a tooth or other abutment fixed thereto, the tooth or abutment of one frame being adapted to register with and engage the notch of another frame whereby a succession of frames may be 60 linked together.

2. In a moving picture machine, a strip having teeth upon one edge to coöperate with the machine mechanism and a groove in another edge to receive the plate edge, 65 both plate and groove being provided with interlocking elements to prevent longitudinal shifting with reference to the strip, and a pressure spring between the plate edge and an inner wall of the groove. 70

3. In a moving picture machine, means for holding a plate adapted to receive or carry a plurality of pictures arranged in rows said plate and holding means having coöperative locking elements respectively attached thereto. 75

4. In a moving picture machine, a strip having teeth upon one edge to coöperate with the machine mechanism and a groove in another edge to receive the plate edge, 80 both plate and groove being provided with interlocking members to prevent mutual shifting.

5. In a moving picture machine, a strip having teeth upon one edge to coöperate 85 with the machine mechanism and a groove in another edge, a plate, a plate positioning member cemented to the edge of the plate and adapted to enter the groove both groove and plate positioning member having interlocking elements to prevent longitudinal shifting with reference to the strip, and a pressure spring between said member and 90 an inner wall of the groove.

In testimony whereof I have hereunto set 95 my hand.

GIANNI BETTINI.
